(57) **CLAIM**

The ornamental design for a stain kit, as shown and described.

DESCRIPTION

FIG. 1 is a top perspective view of the open stain kit embodying our new design, a box containing liquid concentrate in a bottle and powdered activator in a bag;

FIG. 2 is a bottom view of the open stain kit;

FIG. 3 is a top view of the open stain kit;

FIG. 4 is a front view of the open stain kit;

FIG. 5 is a rear view of the open stain kit;

FIG. 6 is a right-side view of the open stain kit;

FIG. 7 is a left-side view of the open stain kit;

FIG. 8 is a top perspective view of the closed stain kit embodying our new design;

FIG. 9 is a bottom view of the closed stain kit;

FIG. 10 is a top view of the closed stain kit;

FIG. 11 is a front view of the closed stain kit;

FIG. 12 is a rear view of the closed stain kit;

FIG. 13 is a right-side view of the closed stain kit; and,

FIG. 14 is a left-side view of the closed stain kit.

The broken lines in the drawings illustrate indicia which form no part of the claimed design.
